Primary Examiner—T. Chase Nelson(74) *Attorney, Agent, or Firm*—Patterson, Thuente, Skaar & Christensen(57) **CLAIM**

The ornamental design for a socket containing device, as shown and described.

DESCRIPTION

FIG. 1 is a perspective view of a socket containing device. FIG. 2 is a slightly reduced scale top view of the socket containing device of FIG. 1.

FIG. 3 is a slightly reduced scale bottom view of the socket containing device of FIG. 1.

FIG. 4 is a front view of the socket containing device of FIG. 1.

FIG. 5 is a back view of the socket containing device of FIG. 1.

FIG. 6 is a first side view of the socket containing device of FIG. 1.

FIG. 7 is a second side view of the socket containing device of FIG. 1.

FIG. 8 is a front cross-sectional view taken along line 8—8 of the socket containing device of FIG. 1; and,

FIG. 9 is a back cross-sectional view taken along line 9—9 of the socket containing device of FIG. 1.

The broken line showing of environmental structure in FIGS. 8 and 9 is for illustrative purposes only and forms no part of the claimed design.
